CLAIM

The ornamental design for a drawer assembly for an appliance, as shown and described.

DESCRIPTION

FIG. 1 is a front view of a first embodiment of the design;

FIG. 2 is a perspective view of a first embodiment of the design in a closed position;

FIG. 3 is a perspective view of a first embodiment of the design in an open position;

FIG. 4 is a front view of a second embodiment of the design;

FIG. 5 is a perspective view of a second embodiment of the design in a closed position;

FIG. 6 is a perspective view of a second embodiment of the design in an open position;

FIG. 7 is a front view of a third embodiment of the design;

FIG. 8 is a perspective view of a third embodiment of the design in a closed position;

FIG. 9 is a perspective view of a third embodiment of the design in an open position;

FIG. 10 is a front view of a fourth embodiment of the design;

FIG. 11 is a perspective view of a fourth embodiment of the design in a closed position;

FIG. 12 is a perspective view of a fourth embodiment of the design in an open position;

FIG. 13 is a front view of a fifth embodiment of the design;

FIG. 14 is a perspective view of a fifth embodiment of the design in a closed position;

FIG. 15 is a perspective view of a fifth embodiment of the design in an open position;

FIG. 16 is a front view of a sixth embodiment of the design;

FIG. 17 is a perspective view of a sixth embodiment of the design in a closed position; and,

FIG. 18 is a perspective view of a sixth embodiment of the design in an open position.

The broken lines showing an appliance and control panel details in FIGS. 1-18 are included for the purpose of showing environmental portions of the drawer assembly for an appliance and form no part of the claimed design.
